UNITED STATES PATENT OFFICE.

FRANK E. MORGAN, OF NEW HAVEN, CONNECTICUT, ASSIGNOR TO THE
NEW HAVEN CLOCK COMPANY, OF SAME PLACE.

DESIGN FOR A CLOCK-CASE.

SPECIFICATION forming part of Design No. 19,868, dated June 3, 1890.

Application filed October 14, 1889. Serial No. 327,017. Term of patent 7 years.

To all whom it may concern:

Be it known that I, FRANK E. MORGAN, of New Haven, in the county of New Haven and State of Connecticut, have invented a new 5 Design for Clock-Cases; and I do hereby declare the following, when taken in connection with accompanying drawing and the letters of reference marked thereon, to be a full, clear, and exact description of the same, and 10 which said drawing constitutes part of this specification, and represents a face view.

This invention relates to a design for clock-cases; and it consists in an octagonal face-board for clock-cases, having inwardly-turned 15 top, bottom, and side divisions and shorter straight corner or intermediate divisions.

In representing my design I have shown a case ready to receive the clock-movement, the dial, and the dial-sash.

20 Referring to the illustration, the top, bottom, and side divisions of the edge of the octagonal face-board A are inwardly curved,

and the shorter intermediate or corner divisions straight. The drop B of the case depends below the curved bottom division of 25 the face-board, and has straight parallel sides and a straight lower edge. As herein shown, the lower corners of the drop are straight to harmonize the corners of the drop with those of the face-board. As herein shown, also, the 30 edges of the face-board and drop are beveled.

The essential and characteristic feature of my design is, however, the inwardly-curved top, bottom, and side divisions of the octagonal face-board. 35

What I claim is—

In the design for a clock-case herein illustrated and described, the octagonal face-board having its top, bottom, and side divisions inwardly curved, as illustrated and described.

FRANK E. MORGAN.
